TELEMETRIC BROADCASTING AND RE-
CORDING APPARATUS

John P. Buckley, Washington, D. C.

Application May 1, 1934, Serial No. 723,393

15 Claims. (Cl. 177—351)

This invention relates, in general, to an apparatus having means for automatically ascertaining the changes in a registering device, such as a thermometer or the like, and for signaling the resultant findings over a conductor or by radio broadcast.

Another object of the invention is the provision of an apparatus to alternately detect such finding in a group of registering devices and while so detecting the condition of each device to automatically record such conditions on a tape as a permanent record thereof or for the purpose of broadcasting the information collectively, at a later time.

Still another object of the invention is the provision of an apparatus which will be especially applicable for isolated spots for reporting meteorological and other conditions. As a specific example I have shown a thermometer and a barometer but it is to be understood that these are merely examples and not a limitation of types of instruments which may be used.

The many novel features embraced in this invention are far-reaching in their scope and are applicable in many embodiments other than that which will be described, and I therefore do not wish to be limited except as indicated by the appended claims.

Figure 1 is a top view of the apparatus.
Fig. 2 is a modification of the code wheel.

Fig. 3 is a front elevation view of a part of the apparatus, showing the application of a single roller and row of contacts.

Fig. 4 is a detail view of the multiple contact plate, rack bar and coordinating parts and cams.

Fig. 5 is a diagrammatic view showing the application of the electric circuits, switch controls, connections to the recording device and radio transmission key controlling the radio transmitting set.

Fig. 6 is a detail view of the upper end of the rack bar, showing the contact roller and multiple contact plate.

Fig. 7 is a front view of the same, showing the application of two rollers and two rows of contacts.

Fig. 8 is a modification of Fig. 5, showing how the same results may be obtained by employing a photo-cell for indirectly energizing and deenergizing the several electromagnets.

Fig. 9 is an enlarged view of the photocell and thermometer.

Fig. 10 is a top view of the thermometer and housings.

Fig. 11 is a partial side view of the paper tape perforating means.

Fig. 12 shows a modification of the circuit make and break member, how it may apply in monitoring a swinging pointer meter.

Fig. 13 is a circuit diagram for the same.

Referring now in detail to the drawings:

The numeral 1 designates the bed plate supporting the standards 2, in which shaft 3 is loosely journaled. Securely fastened on the shaft is gear 4 meshing with the worm 5, of motor 6.

Adjacent to the worm on the shaft is the code wheel 7, peripherally provided with dots and dashes 8, and is made free to revolve on shaft 3, through its loosely mounted elongated hub 9, carrying the gear 10, fixed thereto, the hub having one or more pin holes 11, in its face to engage the pins 12 of slidable clutch member 13, provided exteriorly with a keyway 14, on shaft 3.

Outwardly disposed from gear 10 and meshing therewith for controlling its upward movement in the guide 15, is the rack-bar 16, the rear side of which has ratchet teeth 17, engaged by the spring pressed pawl 18, for the purpose of retaining the bar in its attained height when the power is released.

The two sides 19 of the bar are recessed to slidably fit into the guide 15, which is securely attached to the base.

The top of the rack-bar, Figs. 4 and 7, shown in this case and pivotally attached by screws 21, has an extending arm 22 in the former and in the latter the two arms 22 and 23; the ends are designed to carry the two rollers 24 and 25. The cross arm 26, fixed to the bar, is threaded to engage the adjustable screws 27, the outer ends of which screws bear upon the leaf spring 28, for resiliently pressing the rollers against the terminals 29 and 211 of insulation plate 30. The bottom of the bar has also the insulation piece 31.

The clutch member 13 is normally in the position shown in Figs. 1 and 3 in engagement with the hub 32 of the loosely mounted cams 33 and 34, which it is adapted to drive by means of pin 37. The loosely mounted cams 33 and 34 are held against lateral movement on shaft 3 by suitable means 35, Fig. 3, and the hub 36 of the pinion 38.

The rod 39 is slidably mounted in bearing 38 and carries roller 40 which cooperates with the cam 34 (see Figs. 1 and 4). The rockable member 41, loosely mounted on the vertical shaft 42, has two projecting arms 43 and 44. The arms have slots 45 and 46, of such length, as to pro-

vide freedom of motion for the rods 39 and 47, when pivotally tied by bolts 48 and 49.

The forked head 50 of rod 47 is pivoted to the rod 51, carrying the contact roller 52, and rockably mounted in bearing 53. The spring 54 normally holds the roller from contacting with the code wheel as the roller 40 rests on the flattened portion of the cam 34 when the latter is in normal position. The forward throw of the contact roller across the face of the code wheel 7, which is stationary at this time is brought about when the cam presents its non-flattened face to the roller 40, at which time the spring is under tension so that it will return contact roller 52 to its non-contacting position upon the return of cam 34 to its normal position.

The cam 33, controls the release of the pawl 18 from the rack bar, through the angle rod 55, journaled in bearing 56, and having a projection 57 cooperating with said part. At the instant of release, the bar, through its own weight, falls downward to normal position. As the movement of the rack bar and code wheel are coincident, both members return to normal at the same time. This release occurs at the instant when the key has reached its farthest travel beyond the code wheel to the left, when the code wheel will swing freely around, and come to rest as the contact roller commences to traverse backwardly over the portion of the face of the code wheel not provided with code forming projections.

The hub 32 of the cams 33 and 34, extends to the right of the cams and supports the pinion 58. Meshing therewith is gear 59, carrying the drum switch 60, in which metallic plates 61 and 62 and 214 are embedded—the whole being supported on shaft 63, supported as by bearing 64.

Electrically contacting with the metallic plates 61, 62, and 214, are the brushes 65, 66 and 219, which are held fast on their insulation support 67.

Projecting outwardly from the bearing 64 and fixed on shaft 63 is the pinion 70 which meshes with the large gear 71 provided on the end of the drum switch 72, carrying the metallic plates 73, 74, and 75. The brushes 76, 77, and 78 contact therewith and are also secured to the insulation block 79. The metallic drums 80 and 80' are provided with the insulation blocks 81 and 217 and cooperate with brushes 80'' and 216. The shaft 82, of the drum is journaled in bearing 83, and is provided with the set collar 84 and the cam means which cooperates with arm 44 to form a stop means for the roller key 52.

In addition to the means already described the apparatus mounted on base 1 includes a recorder of the type in which a tape is perforated at intervals and additional contacting means for cooperation therewith to control a delayed transmission of the instrument readings. This means is connected to the main driven shaft 3 by means of an irreversible drive so that it is driven in one direction only. A more detailed description of this means is now given.

Shaft 90 is mounted in spaced bearings 92 and 104 which are fixed to the base 1, a gear 86 is loosely mounted on said shaft and engages with pinion 10 to be driven thereby. A ratchet wheel 88 has its hub pinned to shaft 90 by pin 91. A pawl 87 is mounted on the side of gear 86 and is pressed into engagement with the teeth of ratchet wheel 88 by spring 89. Thus the shaft 90 is driven only when pinion 10 is driving the rack 16 upward.

A clutch member 97 is splined to shaft 90 by spline 98. This member 97 is shifted by the usual

forked lever means operated by an electromagnet 157 and spring 159 (see Fig. 5) which operation will be later described. The electromagnet 157, forked lever 158 and spring 159, schematically shown in Fig. 5, are located below the cylinder 99 when the device is viewed in plan and therefore are not shown in Fig. 1.

A sprocket wheel 93 having a hub 94 is loosely mounted on shaft 90 between the gear 86 and clutch member 97 and held laterally by suitable means such as a set screw or pin not shown. The hub 94 is provided with holes 95 for cooperation with the pins 96 on clutch member 97 when said clutch member is in its left hand position as viewed in Fig. 1. A drum 99 is also loosely mounted on shaft 90 between the clutch member 97 and bearing 104. The end 103 of drum 99 is provided with holes to cooperate with pins on clutch member 97 in a similar manner to the cooperation of holes 95 and pins 96. Drum 99 is provided with a series of pins 100 for cooperation with perforations 101 along the edges of paper tape 102. The member 99 is suitably restrained from axial movement along shaft 90.

A shaft 106 mounted on base 1 parallel to shaft 90 by bearings 106' and 106'' carries a drum 105 similar to drum 99 and having pins 107 like pins 100. This drum is fixed to shaft 106 by suitable means and is driven by means of sprocket wheel 110 mounted on the end of shaft 106. A chain 111 connects the sprocket wheels 93 and 110.

Reference is made to Fig. 11 as well as Fig. 1 for the following description:

The drum 105 when rotated feeds the paper tape 102 from the roll 109 across the die 120 of a 35 punching means from which it may fall in a loop 108. A punch 117 slidably mounted in guide 118 is normally biased to inoperative position by spring means 119. The armature 115 of electromagnet 114 normally biased to inoperative position by spring means 116 cooperates with punch 117 upon energization of said magnet 114 to punch a hole in tape 102. The hole 121 in die 120 is positioned to cooperate with punch 117. The energization of magnet 114 will be later described in connection with the circuit diagrams of Figs. 5, 8, and 13.

Fig. 2 shows how the code wheel 7, when modified, may, in coordination with other parts, such as a perforating die, effect a stamping of a whole 50 letter or number in one movement.

Any ordinary "step by step" movement, not shown, may be employed to move the paper along for other stampings.

The non-magnetic bars 122 and 123 aligned 55 with guide rods 124, and the iron plungers 125, freely journaled, constitute the stamping die. The electromagnet 126 with an extended core 127, serves to attract the iron plungers when energized. Such successive energization of the magnet as might be caused by any kind of rotary switch, affords means for the plungers to faithfully reproduce successively any one of the letters or numbers carried on the face of the code wheel, when presented.

The bottom portion 123, forming the movable head of the die has the dependent rod 128 journaled in bearing 129, and armature 130, in this way, the solenoid 131, when energized, forces the head, beneath the paper, upwardly to engage the 70 plungers, when the perforation of the paper is effected.

Fig. 3 is an elevation view of a part of the apparatus, omitting the perforator and the electromagnets operating the same. The relay magnets 75

132 are shown beneath the base, with armatures 133 pivoted as at point 134 whose cooperation in the system will be later described. The projecting end carries electrical contact 135 oppositely opposed to electrical contact 136 insulated from the base by insulation 137 and kept open when the rack bar 16 seats upon the armature or when magnets 132 are energized and closed during the upward movement of the bar by the spring 138, 10 provided said magnet 132 is deenergized.

The means for electromagnetically operating the clutch member 13, is also shown wherein the armature 139 is held backwardly by the spring 140, anchored to post 141. The armature is pivoted as at 142, while the upper end of the armature links with rod 143, thence to clutch rod 144, which is also pivoted as at base 145. The upper end of the rod is of the usual design for engaging a slidable clutch; forked ends with adjustable 20 screws.

Fig. 5 is a circuit arrangement showing how one or more recording devices, such as the thermometer "a" and barometer "b" may be monitored and the readings broadcasted. The clock switch 146, and the circuit controlling the motor 6, is represented by the conductors 147, 148, and source 149. The rotatable metallic portion 80 of the switch 72 shunts the clock switch through conductors 150 and 151. The insulation insert 81 on the rotatable metallic portion of the switch 72 serves to break the motor current after the shaft 82 or switch has made one cycle, after which time the motor must again be energized by the clock switch or by some similar method.

Describing the operation of the apparatus and referring to Figs. 1 and 5, the clock switch 146 may close at predetermined periods and when so closed the motor 6, which serves to drive the shaft 3, and incidentally shafts 63 and 82, becomes energized. In order to short-circuit the clock switch 146 and to establish a predetermined time limit to the operation a switching means comprising a metallic portion 80 of switch 72 with an insulation insert 81 and brushes 80 is connected across said switch 146 in the following manner: lead 151 connects one brush 80 to negative of battery 149 and lead 150 connects lead 147 to the other brush 80. When the system is in normal condition insulation 81 is under brushes 80 maintaining an open circuit at this point. Upon rotation of shaft 82 when motor 6 is started the metallic portion of switch 72 moves under the brushes 80, short circuiting the clock switch 146 and maintaining the motor circuit closed for one revolution of shaft 82. The adjacent metallic drum switch 80', comprising brushes 216 and insulation insert 217, is of like construction and by cooperating with the leads 215, serves to condition the transmitting set 187 having the antenna 188 and the ground for the key roller 52, as will be hereinafter described.

Next in order, and referring to the drum switches 60 and 72, is the closing of the shunt circuit which is composed of the small metallic plates 214, leads 213 to plate 29. This arrangement of parts serves to shunt the main clutch circuit controlled by the electromagnet 160 as the plate 73 of drum switch 72 moves under the brushes 76. At this instant before the armature, carrying the spring 170, is attracted, the electromagnet 114 is momentarily energized to perforate the paper strip 102 to represent the starting point of the upward travel of the bar. During the time the rack bar is pushed upward the pinion 10 also 75 engages the loosely mounted spur gear 86, carry-

ing the pawl 87, loosely pivoted on the side of the gear as at 89. The pawl engages with the ratchet 88 fixed on the shaft 90, which turns in the one direction only and is held fast on the shaft by the pin 91. The loosely mounted sprocket wheel 5 93, due to the engagement therewith at this time of clutch member 97, by clock switch being closed thus energizing magnet 157, the sprocket chain 111 is drawn, which also surrounds the sprocket wheel 110 fixed on the shaft 106, and supporting 10 the drum 105 to revolve in order to step up the paper strip 102 with each movement of the rack bar, in short, the rack bar, code wheel, and strip of paper are synchronously arranged to keep in step. 15

The main clutch 13, having taken hold the pinion 10, uplifts the rack bar 16 supporting the roller 24, and turns the code wheel 7 around correspondingly to a degree with respect to the alignment of the contact roller 52 across its face until 20 the roller 24 rises above the level line between the point of contact and the top of the mercury column 163 where it loses the current and causes the electromagnet 160 to become deenergized, allowing the spring 170 to again contact with the lead 171, leading to the electromagnet 114, which, on becoming energized, for the second time perforates the paper strip, this time, indicating the height of travel of the bar. The circuit of the punching unit may be traced through the spring 30 170 on the armature of the electromagnet 160, thence through the conductor 171, electromagnet 114, conductor 172, brushes 76, conductors 174 and 148, to the positive side of the source 149. From the negative side of the source, conductors 35 161 and 168, conductor 169 and thence back to the spring 170, as shown.

In this manner the distance between perforation in the paper strip is made to represent the distance traveled by the rack bar and code wheel. 40 Therefore, each successive action of the apparatus is recorded permanently, and, later, through other movements, may be made to automatically repeat such action. As each action causes an additional step forward of the paper strip, the 45 strip eventually forms into a loop 108, Fig. 11.

Upon the main clutch circuit being broken the spring 140 engages clutch 13 with hub 32 and the switch drums 60 and 72 and cams 33 and 34 are again made to rotate by power from shaft 3. The 50 timing of contacts 61, 62 and 214 through their spacing and the ratios of gears 58 and 59 is such that the cams 33 and 34 may make a complete revolution, thus causing the contact roller to pass over the code wheel and return to normal and 55 subsequently tripping the pawl 18 which will permit the rack bar 16 and the code wheel to return to zero, before the main clutch circuit is closed again. To this end the cam 34 moves against the roller 40, which, through the rod 39, angle 60 piece 41 and rod 47, pushes the key roller 52 across the projections 8 of the code wheel.

While traversing over the projections 8, electrical contacts between the roller and projections take place, and signals may be broadcasted. 65 The end 57 of the rod 55 is curved outwardly, as shown in Fig. 4, to push the pawl 18 from the toothed portion 17 of the rack bar, and permit the rack bar and the code wheel to return to zero, the weight of the bar being sufficient to 70 overpower the friction of the code wheel. The reading of the thermometer having been broadcasted the switch 60, shown in detail in Fig. 1, continues to turn until the metallic plate 62 is 75 contacted by brushes 66 which connect wire 213.

with battery 149 and thus contacts 211' are energized through the barometer and leads 212' (see Figs. 5 and 7. The same action, throughout, as recited, takes place in monitoring and broadcasting the height of the column of mercury in the barometer, the smaller plates 214 being common to both instruments in conditioning the circuit for the electromagnet 160. The apparatus is conditioned to monitor and broadcast the findings of each instrument in turn as the plates 61 and 62 are successively engaged, such action has already been described which brings us to the point where the whole may be again broadcasted collectively through the recorder during the second phase of the cycle of the drum 60 when the monitoring is silent the plates not being shown. In this case the cam 85 is omitted from the apparatus. The length of time of the monitoring and broadcasting is determined by the clock switches 146 and 153, which may be made to shunt the insulation 81, on metallic drum 72, otherwise as shown, the action of the whole will stop as the brushes 80" contact with the insulation insert 81, thus completing period of broadcast, which may be renewed by the clock switching means at certain periods. Where the instruments are monitored only for one-half phase of the drum 60 and the cam 85 having its eccentric extension arranged to interrupt the path of the roller 52 may be timed to stay the roller 52 to the left side, during this time, until the beginning of the second half-phase of the cycle when the cam may release the roller and the clock switch 153 may close to energize the auxiliary circuit controlling the electromagnet 157 of the recorder. The circuit for the same consists of the clock switch 153, conductor 155, electromagnet 157, conductor 154 to the negative side of the source 156, and from the positive side of the source to the pivoted end of the switch 153. With the disengagement of the clutch 97 of the recorder from the sprocket wheel 93, the drum 99 turns in engagement with the clutch 97 and advances the paper strip 102 up from the loop 108; beneath the contact roller 112, and thereafter, electrically contacts with the drum 99 as the holes are encountered to complete the circuit through the system. The position of the drums 60 and 72 now renders the roller 24 electrically inoperative, and transfers its control of the electromagnet 160 to the smaller roller 112 of the recorder, which functions, electrically speaking, in the same manner as the roller 24—the distances between the punched holes of the strip of paper moving between the roller 112 and the drum 99 should, in every case, equal the distance of the travel of the rack bar, and hence, a reproduction of the monitoring of the instrument will be broadcasted. The plates 74 and 75 now engaged, forms a part of the circuit through the electromagnets 132 and 160. Tracing the circuit for the electromagnet 132, which is operably associated with the perforations in the paper strip, there is shown plate 74, one brush 77, conductor 179, roller 112, under which the paper strip is drawn, the drum 99, electromagnet 132, conductors 176 to conductors 168, 161 to the negative side of the source 149, from the positive side of the source through conductor 148, thence over conductor 174 which has a short lead to the other brush 77 and to plate 74. This circuit, through the electromagnet 132, is controlled by the paper strip 102, and performs the same service with respect to the operation of the clutch magnet 160 as the column of mer-

cury in the instrument during the time of monitoring. The distance, therefore, between the perforation in the paper strip is analogous to the length of upward travel, in each case, by the roller 24 of the rack bar. To accomplish this end 5 after the roller 24 picks up the current from plate 29 to energize the electromagnet 160, as in Fig. 5, I have provided the armature 133, to which is connected the conductor 184 leading up from one of the brushes 78 which contacts the plate 75. 10

It will be noted that the armature is held downward by the weight of the rack bar which is provided with the insulation 31 in its normal position against the bias of armature spring 138. When the rack bar is raised contacts 136, 137 and 15 lead 181 are allowed to complete the circuit of clutch operating magnet 160. Thus while the paper strip separates drum 99 and contact roller 112, the clutch magnet 160 remains energized in a manner similar to when energized through the mercury column in monitoring the upward travel of the roller 24, when the paper strip moves forward and presents another perforation beneath the roller 112, the electromagnet 132 is energized and draws the armature downward to break the 25 circuit through the electromagnet 160 for another length between the perforations in the paper strip, and so on, until the last perforation arrives at a predetermined position, when the clock switches 153 and 146 will open simultaneously. 30

Fig. 8 shows the clock switch 153, together with the motor circuits and transmitting set conditions, as similarly shown in Fig. 5.

The drums, 60 and 72, may have many plates 35 according to the gear ratio, in this respect, however, I have shown but four metallic plates, 61 and 62, surrounding the one-half phase of the drum; the other side of the drum is left blank except for the smaller plates 214 which are 40 equally spaced around the drum. The plates 73, 74, and 75, on drum 72 are suitably arranged to cooperate with the plates 61, 62 and 214 of drum 60, and the clock switches 146 and 153. 45

The cam 85 is for the purpose of making captive 45 the contact roller 52, and may come on at any prearranged time of the system, as for instance, when it is desired to monitor and record the data during the daytime only, without the broadcast feature, and, later, as during the early part of the 50 night when the static is low, and may be more convenient for the operator, remotely stationed, to listen in for the collected data, at which time the cam 85 goes "off" as the clock switches 153 and 146 go "on", to finish the second half-phase 55 of the cycle, during which time the broadcast of the findings of the day may occur. The cam may be shaped to clear the arm of angle 41 at any time for monitoring, broadcasting and recording with each action of the apparatus, or may 60 be omitted, as the case might be.

Fig. 7 shows how a multiple roller 24 and 25, electrically connected to each other and to the rack bar support 16, may engage a multiple row of metallic buttons 211 and 211' on an insulation 65 panel 30 and electrically connected separately with the plates 61 and 62, as might be inserted in the circuit, Fig. 5. Any number of rollers, on one rack bar, and as many rows of buttons, properly insulated on a panel, may identify a number of instruments successively as the plates 61, 62 et seq. are successively contacted by their respective brushes. 70

In Fig. 8 the main clutch circuit for energizing the electromagnet 60 is slightly modified to

conform to the application of a photocell, which functions in lieu of the roller 24. The cell 194 is housed in the case 193, on top of the rackbar in alignment with the lamp 191, also housed oppositely in the case.

The whole forms a part of the movement of the rackbar. As the rackbar rises the light rays scan one side of the thermometer, the mercury of which forms a shutter for the cell opposite. On reaching the top of the mercury, the light rays pass through the stem uninterrupted to the cell, which on being sensitized through the leads 196 and 197, instantly energizes the relay 198 through—leads 196 and 197, whose armature 199 becomes attracted, and, similarly, as the roller 24 rises above the mercury, the relay breaks the current through the electromagnet 160. The circuit may be traced as follows: the two conductors 164 and 166, leading from source 149, including contacts 65 and the plate 61. From the negative side of the source 149 the conductors 161 and 168 connect with electromagnet 160 and from the magnet through conductor 162, pawl 18, rackbar 16, and therefrom through lead 201 back to the armature 199. With the exception of omitting plates 214, the switch 60 is of the same construction and has the same parts as shown in Fig. 5. The circuit for the electromagnet 114 for recording the perforations in the paper strip is also the same as used in Fig. 5. The circuit used in broadcasting the data, however, on account of the relay application, is different to the extent that electromagnet 132 is omitted, the member 182 taking the place of armature 133, the contacts, etc., being the same as in Fig. 5. From the member 182, when free, the circuit continues through conductor 200 to relay 198, and thence through conductor 200' to roller 112, and through the perforation in the paper to drum 99, thence through conductor 179 through brushes 77, to plate 74, across the plate 74 to the short lead connecting the conductor 174, and through 148 to the positive side of source 149. From negative side of source through conductors 161, 168, to conductor 176, back to armature 182.

The lamp circuit, which is also controlled by the plate 73, is composed of conductors 161 and 195, leading from negative side of source 149 to lamp 191, conductor 194 to conductor 172, brushes 76, plate 73, and conductors 174, 148 to the positive side of source 149. The clock switch 153, and the electromagnet 151, operate in the same way, as in Fig. 5.

Still another modification of the invention for energizing and deenergizing the main clutch electromagnet 160 as in the case of the roller 24, and the photo-cell 194, is shown in Figs. 12 and 13, wherein the swinging pointer type meter 206 is monitored.

The gear 10 is shown in mesh with the teeth of the curved portion of the rackbar 16a which is shaped to swing around freely on a shaft, as at point 209, centrally but independently of the shaft of the meter. The top of the bar is provided with the resilient blade 210, with its top-most portion bent inwardly so as when the pinion 10 turns the rackbar backward the bent portion of the blade will swing forward and electrically engage the pointer 207. As the movement of the blade is synchronized with the movement of the code wheel, the latter will take a position corresponding to that of the meter pointer 207.

At the instant of contact the relay 198 becomes

energized and attracts the armature 199, thereby breaking the current through the electromagnet 160, in the same manner as shown in Fig. 8.

The circuit of the relay may be traced from the blade 210, through the conductor 195', relay 198, conductors 195, 161, to negative side of the source and from the positive side of the source 166 to conductor 148, thence to conductor 174, across plate 73, to conductor 172, thence to conductor 194, and then to pointer 207.

The main clutch circuit, operating the electromagnet 160 is followed from the armature 199, through conductor 164, across plate 61 through conductor 166 to the positive side of source 149, and from the negative side of the source to conductors 161, 168, electromagnet 160, thence through conductor 162 to pawl 18, pinion 10, to conductor 201 and back to the armature 199.

The broadcasting circuit may be traced from plate 74 through brushes 77 to conductor 174, thence to conductor 148 to positive side of the source 149 and from the negative side of the source to conductors 161 and 195, to relay 198, thence through conductor 200 to member 182, conductor 200' to roller 112, drum 99, conductor 179 and through other brush 77 to plate 74.

Fig. 2 shows a modified form of the code wheel 7, which is constructed of non-magnetic material and has an open side to permit the portion 127 of the core of electromagnet 126 to extend inwardly and over the projections 8. Properly spaced beneath the projections are the iron plungers 125 which are loosely supported in the non-magnetic bar 122, held fast to the table top 35 by pins 124. The head 123, attached to the armature 130, forming a part of the non-magnetic rod 128, has a series of holes in alignment with the iron plungers 125. The plungers normally escape the projections 8, but when the magnet 40 126 is energized are drawn towards the projections and spaces between them as shown. Such plungers as are free to become magnetically attracted rise up into the spaces between the projections and when so attracted, do not register when the head 123 is forced upward to take the impression of the plungers as they might array beneath the projections of the code wheel. The paper has a step-by-step motion at right angles to the code wheel, in order to take 45 other impressions of the code wheel. Any suitable rotary switch on the shaft 3, also not shown, may energize the solenoid before each stepping time of the paper.

In Fig. 9, I have shown how the case 191 may be divided into two integral parts, and how the photo-cell may be kept in alignment with the lamp case by the looped arm 202, attached to the photocell case fixed to the head of the rackbar 16. The loop is for the purpose of allowing the thermometer to be displaced by another instrument of similar design when such instruments are mounted on a carriage and passed on successively from the loop after having been monitored. The thermometer is shown coated with black 60 enamel 203 with two slits along its length 204 and 205 to permit the light rays to pass to the photocell. A top view of the thermometer and cases is shown in Fig. 10.

What is claimed is:

1. In a device for broadcasting and recording gage readings, a signalling device, a code element for controlling said signalling device, a sensing device, the movement of which from a reference point is determined by the gage read-

- ing, a recording tape, electro-mechanical means positively driving the code means, the sensing means and recording tape in synchronism from the reference point; perforating means associated with said recording tape, said electro-mechanical means including a first switch drum and a second switch drum, an electro-magnetically operated clutch, spring biased to normally drive said switch drums, an electric motor and a periodic circuit closer; a first electric circuit controlled by said periodic circuit closer for initially energizing said motor, a second electric circuit including certain contacts of said first drum switch for shunting said periodic circuit closer, a third circuit including the sensing means and certain contacts of the second drum switch, for shifting said clutch to disengage the drum switch drive and drive the code means, the sensing means and the recording tape; a fourth electric circuit including contacts controlled by movement of said clutch for operating the aforesaid perforating means while the sensing means is still at its reference and when the sensing means determines the gage reading whereby the gage reading is recorded.
2. The device of claim 1 in combination with a rebroadcasting device including a tape-receiving drum for the recording tape and means associated therewith for controlling the code element through the aforesaid electro-mechanical means in accordance with the record previously made thereon.
3. In combination with a code wheel, a motor-driven shaft on which the wheel is freely mounted, cams and gears mounted freely on said shaft, certain of said gears fixed to rotate with said wheel and another of said gears fixed to rotate with said cams, a sensing device and a recording device geared to said first named gear, a first drum switch geared to said second named gear and a second drum switch associated in fixed angular relation with said first drum switch, a clutch associated with said motor driven shaft and biased to drive said cams from said shaft, said clutch having a contact means associated therewith, electric means including one of said drum switches and said sensing device for controlling said clutch, second electric circuit means including the other drum switch and said clutch contact means for controlling said recording device, locking means for holding said sensing means and code wheel in a given position, key means for cooperating with said code wheel, one of the aforesaid cams being constructed and arranged to operate said key means while the code wheel is held and the other of said cams being constructed and arranged to release said locking means after operation of the key means.
4. In a device of the character described, a gage having a pointer movable from a reference point, a coding device angularly movable from a reference point, means associated with the gage also angularly movable from the gage reference, means associated with the first named means and the coding device to transmit proportional movement from the first named means to the code device.
5. In a device for broadcasting recorded data, a variably positioned element, means for making a record of the position of said element, a code carrying element having a movement in one direction and being provided with code producing elements, said code producing elements being arranged in code groups substantially transverse to the said direction of movement of the code carry-

ing element, keying means including an element movable over each code group, means for positioning said carrying element in accordance with said record.

6. In apparatus of the character described, a pointer, means to move the pointer in response to change in meteorological conditions, sensing means movable from one reference point to engage the pointer, code selecting means set by the amount of movement necessary for the sensing means to engage the pointer, signal emitting means, means controlled by the code selecting means to control the signal emitting means.

7. In combination with the system of claim 6, a recording means to record proportionately the amount of movement of the sensing means simultaneously with the movement of the sensing means, means to subsequently reset said code selecting means by said recording means to a position corresponding to the code selected at the time the recording means recorded, means controlled by the code selecting means to again control the signal emitting means.

8. In apparatus of the character described, an independently movable variable element, sensing means to periodically move to sense the variable element from one reference point, code selecting means operated to select a code in accordance with each sensing of the sensing means.

9. In combination with the apparatus of claim 8 a recording means simultaneously operated with the sensing means, means including the recording means to subsequently reoperate the code selecting means to select the same code as that code which was selected when the recording means was operated.

10. In apparatus of the character described, an independently movable element, a code selecting means, circuit means to control the code selecting means including a light responsive means, means to move the light responsive means to sense the limit of the movable element from one reference point.

11. In combination with system of claim 10 a recording means to proportionately record the total movement of the sensing means simultaneously with the movement of the light responsive means, means including the recording means to subsequently reset the code selecting means to a position corresponding to the code previously selected at the time the recording means recorded.

12. In apparatus of the character described, an instrument for measuring variable conditions having a movable pointer, means to move the pointer in response to change in conditions being measured, sensing means associated with said instrument and movable from one reference point to engage the pointer, code selecting means set by the amount of movement necessary for the sensing means to engage the pointer, signal emitting means, means controlled by the code selecting means to control the signal emitting means.

13. In combination with the system of claim 12, a recording means to record proportionately the amount of movement of the sensing means simultaneously with the movement of the sensing means, means to subsequently reset the code selecting means by said recording means to a position corresponding to the code selected at the time the recording means recorded, means controlled by the code selecting means to again control the signal emitting means.

14. In an apparatus for transmitting signals corresponding to a gage reading, a rotatable main

shaft, electric motor operated means for rotating said shaft, a cylindrical signaling member loosely mounted upon said shaft and having a plurality of groups of coding contacts, a cam 5 means loosely mounted upon said shaft, main clutch means carried by said shaft between the signaling member and the cam means for selective driving of each of these means, said clutch means being normally biased to drive said cam 10 means, electromagnetic means for shifting the clutch means to drive said signaling member, a gage having an indicating element, movable in a defined path, an exploring means movable along said gage path to a position corresponding to that 15 of the indicating element and geared to said signaling member for movement therewith, a latch for holding the exploring means in said position and means cooperating with the cam means for releasing said latch, a keying device comprising 20 a contact means mounted for movement across said signaling member and cooperating with the coding contacts and having actuating means controlled by said cam means to effect said movement after the exploring means has reached the latched 25 position, a recorder drum and transmitter control drum, irreversible coupling means for driving said drums individually from the signal member, only when said member is driven by the main clutch means, including an auxiliary clutch means normally biased to drive the recorder drum and shiftable by a time controlled means to drive

the other drum, a record ribbon, means on said drums for cooperating with said ribbon, whereby it is driven by said recorder drum toward the other drum to form a loop there-between and subsequently driven by said other drum to take up 5 the loop, a marker means adjacent the recorder drum and means for causing said marker to mark said ribbon when the exploring means reaches its latched position, contact means cooperating with the transmitter control drum and the record 10 ribbon for controlling the keying device, a signal transmitting apparatus including the keying device as its control means and drum switch means driven from the main shaft and connected to the various parts of the system for determining the 15 time of operation of each of said parts.

15. In an apparatus of the character described, means for periodically determining meteorological conditions, means for making a record of the conditions as they are determined, a broadcasting apparatus, means for operating the broadcasting apparatus in response to the said determination of meteorological conditions to broadcast the conditions determined, and means selectively operable for operating the broadcasting 20 apparatus to broadcast signals from said record whereby the determination of said meteorological conditions between selected operations of the last mentioned means will be broadcast.

JOHN P. BUCKLEY.
